UNITED STATES PATENT OFFICE.

SIMON W. WARDWELL, OF PROVIDENCE, RHODE ISLAND, ASSIGNOR TO WARDWELL BRAIDING MACHINE COMPANY, OF PORTLAND, MAINE, A CORPORATION OF MAINE.

STOP-MOTION FOR BRAIDING-MACHINES.

1,172,329.

Specification of Letters Patent.

Patented Feb. 22, 1916.

Original application filed March 17, 1911, Serial No. 615,076. Divided and this application filed August 8, 1913. Serial No. 783,806.

To all whom it may concern:

Be it known that I, SIMON W. WARDWELL, a citizen of the United States, residing at Providence, in the county of Providence and 5 State of Rhode Island, have invented certain new and useful Improvements in Stop-Motions for Braiding-Machines, of which the following is a specification.

My invention relates to braiding machines 10 and particularly to the stopping and braking mechanism thereof.

The present improvement consists of means for actuating the brake-ring to cause the operation of the clutch-device and to apply 15 resistance to the moving parts as described in my prior Patent No. 1,008,504 for braiding machine dated November 14, 1911, and my pending application, Serial No. 615,076, filed Mar. 17, 1911, from which the 20 present case is divided.

The object of my improvement is to simplify the structure and lessen the cost of manufacture of the several parts of the mechanism as hereinafter explained.

25 The manner and means for carrying out my invention are fully set forth in the following specification, illustrated by the accompanying drawings, in which:—

Figure 1 is a view of a portion of the 30 stopping-mechanism of the braiding machine showing my improved actuating-devices applied thereto. Fig. 2 is a detail view of the same, showing certain of the parts in section on the line A—A of Fig. 1, 35 looking in the direction indicated by the arrow α .

As described in my pending application above referred to the essential elements of the braiding machine consist of a central 40 standard or main frame 5 on which are mounted two oppositely-rotating turrets adapted to carry the yarn supplies. These parts are shown more particularly in my U. S. Patent No. 1,008,504 dated Nov. 14, 1911, 45 and are not here illustrated in detail. The turrets are rotated from a main drive-shaft provided with a suitable driving-element, such as a belt pulley, and the rotation of the shaft is controlled through a clutch-mechanism as usual.

The clutch-mechanism of the machine is operated from the movement of a brake-ring 55 which also acts to check the rotation of the turrets after the disconnection of the

driving-means. The brake-ring 55 is mounted on the frame 5 of the machine and is normally held stationary and away from engagement with the turret 61 upon which it impinges. Referring to Fig. 2 of the drawings, the brake-ring 55 is preferably held on an annular flange or bearing 56 surrounding the frame 5 and is adapted to slide rotatively to a limited extent in the direction indicated by the arrow c , Fig. 1. The upper portion of the ring 55 is formed on its interior with an annular, beveled face 68 adapted to engage with an oppositely-beveled surface 69 on the turret 61. The rotary movement of the ring 55 is initiated through the operation of one or more rockable brake-arms 62 which coact with suitable drop-wires mounted on the turrets and controlled by the yarns delivering from the supply-cops. The arrangement of the drop-wires for the several yarns is shown and described 75 in my pending application, Serial No. 605,266, filed Jan. 28, 1911, and will not be here explained in detail as it is sufficient to state that when a drop-wire is released it operates the feeler-levers 57 as later described.

Referring to Fig. 1, 60 designates a bracket which is mounted on the turret 61 and revolves with the latter about the axis of the machine in the direction indicated by the arrow c . There are several of these brackets spaced around the periphery of the turret 61, preferably a number equal to the number of supply-cops carried on the turret. The feeler-lever 57 is pivoted at 58 in a bearing on the bracket 60 and is adapted to be tilted to bring its lower end into the path of the upstanding brake-arm 62. The arm 62 is pivoted at 63 on the base of the machine frame 5, and preferably there is the same number of brake-arms as there is feeler-levers, spaced equidistantly around the machine. The arm 62 is connected to move the brake-ring 55 by means of a stud 64 screwed into the ring with its head 65 projecting through a slot 66 in the arm. To render the arm 62 light of weight and easy to manufacture it is constructed of sheet-metal and its upper end is twisted at right-angles to its body portion to form an offset head 67, see Fig. 2. The brake-ring 55, as before explained is mounted on the flange or bearing 56 with its interior, beveled

face 68 adapted to be frictionally engaged with the beveled face 69 of the rotating turret 61. This engagement is effected by the rotary movement of the ring which causes it to be raised from its bearing 56 as now explained: Fastened to the ring 55 is a wedge-block 71 which is formed with a beveled face 72 adapted to engage an oppositely-beveled face 73 on a projection 74 of the wedge-block 75, the latter being secured to the base of the machine frame 5. The wedge-blocks 71 and 75 are constructed and secured in position in a novel manner as now described.

Both the ring 55 and frame 5 are provided with circumferentially-extending grooves, designated 76 and 77, respectively, and the wedge-blocks 71 and 75 are formed with projections or splines fitted to these grooves. Preferably the wedge-blocks are constructed of sheet-metal and the projections are formed by indenting the metal on one side to force it out on the other. In this way the projections 78 and 79, see Fig. 2, are formed at the same operation as the stamping out of the blocks through the employment of suitable punches and dies in a usual type of drop-press. The block 75 is secured to the base 5 by a screw 80 and the two projections 79, spaced some distance apart and fitting the groove 77, hold the block from turning on the screw. The arm 62 is preferably pivoted on the block 75 by the rivet 63 to obviate the necessity of tapping a hole in the base 5. The block 71 is secured to the brake-ring 55 by the same stud 64 which engages the slot in the arm 62. The shank of the stud 64 extends through a slot 81 in the wedge-block 71 and its head is screwed against the face of the block to bind the latter against the ring 55. The slot 81 allows the block 71 to be adjusted laterally in relation to the block 75, so that the beveled faces 72 and 73 may be set to engage each other at the proper time and, as in the case of the block 75, the projections 78 are fitted to the slot 76 and prevent the block 71 from turning on the stud 64. It will be seen that the novel construction just described shows marked improvement over previous devices as the parts are much simpler and can be manufactured at less cost. Furthermore, only two screws are necessary for the whole arrangement, one of them being adapted to serve two purposes. The operation of the device is as follows:

When a drop-wire is released, through the breaking of the yarn, exhaustion of the supply, or from any other cause, it will act to tilt the first feeler-lever 57 with which it comes into contact. As the lever 57 is tilted its lower end wipes across the top of one of the brake-arms 62 and the latter is rocked 65 in the direction indicated by the arrow *d*,

Fig. 1. This movement of the arm 62 prys the brake-ring 55 a relatively short distance around the bearing 56, and carries the wedge-block 71 against the block 75 so that their beveled faces 72 and 73 are in contact. During this initial movement of the ring 55 under action of the arm 62 the stopping-mechanism of the machine is actuated to release the driving-element from connection with the drive-shaft as fully explained in my pending application herein first referred to. At the same time, instrumentalities are set into action to continue the rotation of the brake-ring beyond the movement imparted through the arm 62. This latter movement of the ring 55, caused by the action of a spring as explained in the above noted, pending application, causes the face 72 on the wedge-block 71 to ride up the face 73 of the block 75, and since there are a number of similar wedges around the machine, all acting in conjunction, the ring 55 will be raised into contact with the turret 61. Now, as the beveled face 68 on the brake-ring comes into contact with the face 69 on the turret 61 the friction between the two will have a tendency to rotate the ring 55 still farther to intensify the thrust of the wedge-blocks and in this way a cumulative braking force is secured. The friction of the ring 55 against the turret 61 serves to check the rotation of the latter and also acts to force this turret against the other one, arranged above it but not here shown, so that a maximum braking force is exerted on both turrets and the moving parts are quickly brought to a full stop.

It will be observed that the parts of the device herein specifically described are of a novel structure and so designed as to give maximum strength with minimum weight. Furthermore, they are particularly adapted for simple methods of manufacture at a relatively cheap cost through the use of stamping dies. In addition, the arrangement of the parts and the method of assembling them provides for the least possible number of screws, bolts, pins or the like and therefore the cost of manufacture of the whole machine is lessened to a considerable extent.

Various modifications might be made in the form and construction of my new device without departing from the spirit or scope of the invention.

Therefore, without limiting myself to the exact embodiment herein shown and described, what I claim is:

1. In a braiding machine, the combination with the braiding-mechanism, of stopping means for arresting the operation of the braiding-mechanism comprising a base 5 and ring 55 mounted on the base, said base and ring formed with peripheral grooves 77 and 76, members 71 and 75 constructed of sheet-metal with lugs 78 and 79 formed by

indenting the metal on one side to force it out on the other, said lugs fitted to the grooves to hold the members from turning, and screws 64 and 80 to secure the members 5 in position on the base and ring.

2. In a braiding machine, the combination with the braiding-mechanism, of means for arresting the operation of said mechanism comprising a member 55 having a groove 76, a member 71 constructed of sheet-metal with projecting lugs 78 engaging the groove 76, said lugs formed by indenting the metal on one side to force it out on the other.

3. In a braiding machine, the combination with the braiding-mechanism, of means for arresting the operation of said mechanism comprising a base 5 formed with a groove 77, a ring 55 mounted on said base and formed with a groove 76, a wedge-block 20 71 having lugs 78 engaging the groove 76, a stud 64 for securing the block 71 on the ring, a second wedge-block 75 having lugs engaging the groove 77, a screw 80 for se-

curing the block 75 on the base 5, and an arm 62 pivoted on the block 75 and formed with 25 a slot 66 adapted to be engaged by the head 65 of the stud 64.

4. In a braiding machine, the combination with the braiding-mechanism, of means for arresting the operation of said mechanism comprising a base 5, a brake-ring 55 mounted to turn on said base, a wedge-block 75 secured to said base, an arm 62 pivoted on the block 75, a second wedge-block 71 adapted to coöperate with the block 75 when the 35 ring is turned on the base, and a stud 64 for securing the block 71 on the ring 55, said stud engaging the arm 62 to adapt the brake-ring to be moved from the arm.

In testimony whereof I affix my signature 40 in presence of two witnesses.

SIMON W. WARDWELL.
